TRAY FOR HOLDING CONFECTION FORMING MOLDS OR THE LIKE

Ben E. Rasmusson, 12510 SE. 62nd Place,
Bellevue, Wash. 98004

Filed Dec. 23, 1966, Ser. No. 5,171

Term of patent 14 years

(Cl. D44—1)

FIG. 1 is an isometric view showing my new design;
FIG. 2 is an end elevational view thereof;

FIG. 3 is a top plan view thereof; and

FIG. 4 is a side elevational view thereof.

The reverse side and end views not shown are identical to those shown.

The dot-dash line showings of the molds in FIGURES 1, 2 and 4 are merely for illustrative purposes.

I claim:

The ornamental design for a tray for holding confection forming molds or the like, substantially as shown and described.
